MORTON SULTZER, OF BROOKLYN, NEW YORK, ASSIGNOR TO WESTERN ELECTRIC COMPANY, INCORPORATED, OF NEW YORK, N. Y., A CORPORATION OF NEW YORK.

METHOD AND MEANS FOR CORRECTING IRREGULARITIES IN TRANSMISSION-LINES.

1,387,210.

Specification of Letters Patent.

Patented Aug. 9, 1921.

Application filed December 18, 1916. Serial No. 137,601.

To all whom it may concern:

Be it known that I, MORTON SULTZER, a citizen of the United States, residing at Brooklyn, in the county of Kings and State of New York, have invented certain new and useful Improvements in Methods and Means for Correcting Irregularities in Transmission-Lines, of which the following is a full, clear, concise, and exact description.

10 This invention relates to a method and means for correcting irregularities in transmission lines, the object being to provide a method and means for correcting irregularities in transmission lines wherein a multiple condenser may be employed in which the capacity of any unit may be adjusted without altering the capacity values of the remaining units.

Although this invention will hereinafter be described in connection with toll cables in telephone systems, it is to be understood that it is not so limited but may be used with any suitable electric network.

This invention is particularly adapted for building out condensers for use in telephone circuits made up of associated conductors as in the case of twisted pairs included in a telephone cable where a group of four conductors constitutes what is called a quad. 30 In such a case, each two-conductor pair furnishes a physical transmitting circuit, while these circuits, taken with the conductors of each in parallel, give a third pair of conductive elements, constituting what is usually known as a phantom circuit.

In such a telephone system, especially when the cable is divided into uniformly loaded sections with inductances inserted at regular intervals, a section of the cable is 40 frequently found, the electrical constants of which do not accord with the constants of the other sections, thus making the cable non-uniform. Such would be the case when the distance between one end of a standard section and a receiving or transmitting station is unavoidably less than the length of a standard section. The connecting of the end of the standard section with the station by means of a short section would mean a 50 non-uniformity in the system unless an artificial means is used to increase the capacity of this short section to the values required.

The necessity of obtaining a loaded tele-

phone system free of non-uniformities lies in the fact that, unless the cable is quite uniform, it cannot be balanced properly by an artificial network, thus preventing satisfactory repeater operation.

This increase of capacity could be added by means of building-out condensers of the type described in the Wheeler-Sultz Patent No. 1,200,063, dated October 3, 1916; but if they are used, a separate condenser will be required for each capacity which is to be adjusted. For various reasons such a large number of condensers, as would be required by the use of the above mentioned type for making the electrical constants of a cable section accord with the constants of the standard sections and for correcting the "capacity unbalance" between certain of the conductors of the section, would be objectionable, as, for example, when they were added to the cable at a manhole where the available space is necessarily limited. This invention overcomes these objections by providing a more compact and effective means than has hitherto been known, for adding the necessary capacities to the cable, and for making the final adjustment of the values of the various capacities for eliminating the "capacity unbalance".

In a cable quad containing two twisted pairs of conductors, there are four kinds of capacities to be considered, namely, mutual capacity, direct capacity, grounded capacity and capacity to ground. By direct capacity is meant the capacity between two conductors when all the other conductors are absent, that is, the so-called geometric capacity. By mutual capacity is meant the total capacity between the two conductors as used, that is, it will be the sum of the direct capacity between the two wires and the additional capacity due to the capacity of each of the conductors to some other object or objects. By grounded capacity is meant the capacity between two conductors when one of the conductors and all other objects in the vicinity are grounded. Grounded capacity will not be used in the following specification, but the term "capacity to ground", as used, will refer to the direct capacity of the conductor under discussion to the cable sheath or other conductors which might be permanently connected to ground.

On a quad there will be six direct capacities and four capacities to ground. Between each two wires the mutual capacity will be the direct capacity between the wires and the 5 additional capacity due to the network of conductors. The four capacities to ground are generally very small and their effect on the mutual capacity of a network of conductors may, in general, be neglected.

10 In a cable quad, in general, the necessity does not exist for absolute adjustment of all six of the direct capacities to a high degree of accuracy, but it is preferable that the 15 four of the direct capacities, which enter into the "capacity unbalance" of a cable, should be relatively adjusted to a high degree of accuracy. By these four capacities is meant the direct capacity between each wire of one pair, and each of the two wires of the other 20 pair. Even after the units have been accurately adjusted to the values for properly "building out" the section, it is necessary to make a final adjustment of some in order to obtain this relative adjustment with a high 25 degree of accuracy. Especially is this true in the case of the four capacities referred to above in connection with the elimination, as far as possible, of cross talk; and they should have values which do not differ from each 30 other by more than a few micro-microfarads.

This invention affords a means for the addition of the desired extra capacity values to a short section of a cable by the addition of two small compactly-built condensers to each cable quad, each condenser containing three units. The construction of each condenser is such that the value of any unit may be varied without causing any variation in the value of the remaining units. This independent variation may be accomplished by pulling in or out one of the plates of the unit to be varied. The fact that this variation does not affect the other units is due to shielding plates inserted between the units as 45 hereinafter described.

This invention may be better understood by reference to the accompanying specification and drawings, in which Figure 1 shows a cross-sectional view of a four-wire core or 50 quad of a cable, and the various capacities of such a system of conductors. Figs. 2 and 3 each illustrate an embodiment of this invention.

Fig. 1 shows a cross-sectional view of a 55 cable quad in which there are four wire conductors, designated by 4, 5, 6 and 7, surrounded by a suitable sheath or covering 18; wires 4 and 5 forming one physical telephone circuit and wires 6 and 7 forming the other. 60 If the two conductors of each pair are connected in parallel, each pair may also be considered as a single conductor, so that the two pairs may be used for the so-called phantom circuit arrangement. Between any wire and 65 each of the other three wires of the quad,

there will be a certain amount of direct capacity. Consider that these capacities between the wires of the quad, represented by Fig. 1, are smaller than those of the standard section, and that condensers 8 to 13 inclusive have been added to the quad to increase them to their proper values. The condensers 14, 15, 16 and 17 between the various wires and the sheath 18 will be described later.

Figs. 2 and 3 show the two multiple condensers of three units each, whose units are attached to the cable quad. These condensers will be described in detail. In Fig. 2, between clamping arms 19, 19 are insulating material 40 and conducting sheets 20 to 27 inclusive. In Fig. 3, between clamping arms 19, 19 are insulating material 40 and conducting sheets 30 to 37 inclusive. The sheets 20—21 form the condenser 10; sheets 22—25 inclusive form condenser 9; and sheets 26—27 form the condenser 12. Corresponding sheets in Fig. 3 form the condensers 11, 8 and 13, respectively. As previously stated, assume that these condensers have been added to the section of a cable quad, as shown in Fig. 1, to increase the various capacities. Such being the case, conducting sheets 20, 33, 35 and 36 would be connected to wire 4; sheets 27, 31, 32 and 34 to wire 5; sheets 30, 21, 22 and 24 to wire 6; and sheets 37, 23, 25 and 26 to wire 7. Each outer sheet of the two multiple condensers has a certain capacity effect to the clamping arm 19, and these capacities for the outer sheets 20, 30, 27 and 37 have been represented in Fig. 1 by the condensers 14, 15, 16 and 17, respectively. These serve to increase the capacities to ground of the wires and to build them out approximately to their proper values for eliminating the non-uniformity, although, being very small, their accurate adjustment is generally unnecessary.

As has been previously stated, it is of the utmost importance that the direct capacities be adjusted to the highest degree of accuracy. Even when the capacity of each unit is previously calculated and constructed for the proper value, after the units are placed between the clamping arms, additional adjustment is generally necessary to obtain the required accuracy, and such adjustment must be made without interfering with the capacity balance in the network; that is, it must be possible to vary the direct capacity of a unit without affecting the capacity of any other unit. Considering unit 10, if we should vary the effective area of sheet 20 by moving it in or out, the capacity to ground of wire 4 would be affected, but if sheet 21 is adjusted, the capacity to ground would be shielded by plate 20, and the capacity 120 9, represented by sheets 22—24 and 23—25, would be shielded from any disturbance by means of sheet 22 which is at the same potential as sheet 21. For, if sheet 130

22 were absent, there would be electrostatic lines of force between sheets 21 and 23, so that the variation of the effective area of sheet 21 would change the number of lines of force to sheet 23. But, by the interposition of plate 22, connected to the same wire as plate 21, and, therefore, at the same potential, there would be no lines of force between sheets 21 and 22, although there would be lines between sheets 22 and 23; but these latter mentioned lines of force will not be varied by movement of 21 as there are no lines between sheets 21 and 22, and so the capacity of the unit 9 would remain unchanged. Furthermore, if sheet 22 were not present, an increase in the effective area of sheet 21 would not only affect the capacity of units 9 and 10, but would also increase the capacity between sheets 20 and 23, or between wires 4 and 7. But as previously explained, the additional capacity to be inserted between wires 4 and 7 is to be derived only from unit 13 of Fig. 3. Hence, this increase in the capacity between sheets 20 and 23 would necessitate a corresponding decrease to be made in the value of unit 13 in order to bring it back to its original value. Thus it is seen that, in the absence of the sheet 22, a variation in the direct capacity value between wires 4 and 6 produces a corresponding change in the mutual capacity between wires 4 and 7. However, with sheet 22 present, the direct capacity of unit 10 may be independently varied.

35 The plate 22, which is at the same potential as the plate that is varied, is shown as a constituent member of the unit 9 and in close proximity to the other plates of said unit, but such need not be the case as it will perform its proper function of acting as a shield between the units 10 and 9 by being placed in any suitable position between the units, providing only that it is at the same potential as the plate that is to be varied.

40 In general, the sheet 22 need not be a member of either of the units, although it is shown as such in the drawings. Therefore, the interposition of a shielding plate between the two adjacent units permits the variation of one without affecting the direct capacity of any of the other units.

45 By similar reasoning the variation of the effective area of sheet 26 will change the capacity of unit 12 between sheets 26 and 27, but will not affect the capacity of any of the other units. In the same manner, unit 11 may be varied by means of sheet 31 and unit 13 by means of sheet 36. The adjustment of units 8 and 9 is easily made, since the two inner plates of each may be varied without affecting the capacity of the other units on account of the protecting plates 22-25 and 32-35, respectively. It is to be noted that there is considerably more insulation between the separate units than between the

plates of each individual unit. This also aids in allowing the independent variation of the units as it reduces a negligible quantity any "fringing" effect around the edges of the plates.

70 The conducting sheets or plates are preferably made of copper, although they may be made of tinfoil or other suitable material. The insulating material may be of sheets of mica or any other insulator.

75 Although this invention is explained with reference to a condenser having only three units, it is obvious that the invention is not so limited, but applies equally as well to a condenser having any number of units.

80 What is claimed is:

1. A unitary multiple condenser structure comprising a plurality of units in such close proximity to each other as ordinarily to establish an electrostatic relation therebetween, and comprising means for varying the capacity of one unit without affecting the capacity of another of said units.

85 2. A unitary multiple condenser structure comprising a plurality of units, means for varying the capacity of one unit and means for preventing the variation of said unit from affecting the capacity of a neighboring unit, said last mentioned means comprising a protecting shield which cuts off the lines 90 of force between said first mentioned unit and its neighboring unit.

95 3. A cable quad comprising a plurality of conductors, each pair of conductors having a direct capacity and a mutual capacity, and a plurality of unitary condenser structures 100 comprising means individual to each of said structures and independent of the others of said structures for varying the direct capacity between a pair of said conductors 105 without affecting the mutual capacity between another pair.

110 4. A unitary multiple condenser structure comprising a plurality of units each unit being composed of a plurality of conducting sheets separated by a suitable dielectric, said units being separated from each other by a metallic shield which serves to cut off the lines of force to adjacent units, whereby 115 the capacity of a unit may be varied without affecting the capacity of any other of said units.

120 5. A cable quad composed of a plurality of conductors, each pair of conductors having a direct capacity and a mutual capacity, and means for increasing the direct capacity between a pair of said conductors without 125 affecting the mutual capacity between other conductors, said means consisting of a unitary multiple condenser structure comprising a plurality of units, said units composed of conducting sheets separated by suitable insulating material, the outer sheet of each unit being at the same potential as the nearest sheet of the adjacent unit, thereby afford- 130

- ing a means for adjusting each unit without affecting the capacity of any other of said units.
6. A unitary multiple condenser structure containing a plurality of units composed of sheets of conducting and insulating material, and comprising means for varying the capacity of one unit without affecting the capacity of another of said units.
- 10 7. A unitary multiple condenser structure, comprising a plurality of units in such proximity that ordinarily they would be in inductive relation, and comprising means electrically connecting adjacent armatures 15 of different units and maintaining them at the same potential, the area of which is provided by the opposed positions of said armatures being adjustable in amount.
8. A unitary multiple condenser structure 20 containing a plurality of units in such proximity that ordinarily they would be in inductive relation, and comprising means electrically connecting adjacent armatures of different units to one terminal of the condenser so that the same polarity is represented by the said armatures, the area which is provided by the opposed portions of said armatures being adjustable in amount.
9. A unitary multiple condenser structure 25 composed of a plurality of units each of said units consisting of conducting sheets separated by a suitable dielectric, means for varying one of said units, and means for preventing said variation from affecting a neighboring unit, comprising a common terminal for the two outermost conducting sheets of the two neighboring units.
10. The method of correcting irregularities in sections of transmission lines which 30 comprises inserting a corrective impedance in a section between the sheath and a wire of said line to bring the value of the impedance therebetween to a desired value.
11. The method of correcting irregularities in loading sections of transmission lines 35 which comprises inserting in an irregular section a corrective impedance between the sheath of said line and a wire therein of such value as to render the irregular section electrically equivalent to a normal section.
12. The method of correcting irregularities of loading sections of periodically loaded transmission lines which comprises inserting 40 between the wires of said lines and the sheath in irregular sections a corrective impedance of such value as to render the irregular section electrically equivalent to a normal section.
- 60 13. The method of correcting irregularities in loading sections of periodically loaded transmission lines which comprises inserting between the sheath and the wires in said line in irregular sections a corrective 45 impedance of such value as to render the irregular sections electrically equivalent to a normal section.
- irregular sections electrically equivalent to a normal section, and inserting corrective impedance between the wires in said lines for the same purpose.
14. A transmission cable comprising a wire and a sheath and comprising a plurality of sections one of which is irregular, and a corrective impedance connected between the sheath and wire in said irregular section, of such value as to bring the impedance 75 between the sheath and the wire in said irregular section to a desired value to thereby correct the irregularity.
15. A transmission cable comprising a wire and a sheath and comprising a plurality of loading sections, one of which is irregular, and a corrective impedance connected between the sheath and the wire in said irregular section of such value as to render the irregular section electrically equivalent 80 to a normal section.
16. A periodically loaded transmission line comprising one or more wires and a sheath, and comprising one or more irregular sections, and a corrective impedance connected between the wires and the sheath in irregular sections, of such value as to render the irregular sections electrically equivalent 90 to a normal section.
17. A transmission cable comprising a wire and a sheath, and comprising a plurality of loading sections, one of which is irregular and a corrective capacity connected between the sheath and the wire, in said irregular section, of such value as to render the irregular section electrically equivalent 95 to a normal section.
18. A periodically loaded transmission line comprising one or more wires and a sheath and comprising one or more irregular sections, corrective impedance connected between the sheath and the wires in irregular sections, and corrective impedance connected between the wires in said irregular sections, said impedances being of such value 100 as to render the irregular sections electrically equivalent to normal sections.
19. A transmission cable comprising a plurality of wires and a sheath, corrective capacities between said wires and said 110 sheath and between said wires.
20. A unitary multiple condenser structure comprising a plurality of units in such proximity to each other that ordinarily they would be inductively related, the mutual capacities between units being of importance, and said structure comprising conducting members arranged for varying the direct capacity of the unit without affecting the mutual capacities between units.
21. A unitary multiple condenser structure comprising a plurality of units in such proximity to each other that ordinarily they would be inductively related, said structure comprising relatively adjustable conducting 115 members.

sheets for varying the direct capacity of a unit without affecting the mutual capacities between units and having considerably more insulation between the separate units than between the armatures of each individual unit.

22. A cable quad comprising two pairs of conductors in a sheath and two unitary multiple condensers, each condenser including three units, one outside unit of one condenser being connected between one conductor of one pair and one conductor of the other pair, the other outside unit of said one condenser being connected between the other two conductors, the middle unit of said one condenser being connected between the two conductors of said one pair, the other condenser being correspondingly connected and adjacent armatures of the different units in each condenser being relatively adjustable and being electrically connected together.

23. A cable quad comprising two pairs of conductors in a sheath, and two unitary mul-

25 tiple condensers each condenser including conducting sheets and three condenser units between said sheets, one outside unit of one condenser being connected between one conductor of one pair and one conductor of the other pair, the other outside unit of said one condenser being connected between the other two conductors, the middle unit of said one condenser being connected between the two conductors of said one pair, the other condenser being correspondingly connected, adjacent armatures of the different 35 units in each condenser being relatively adjustable and being electrically connected together, the armatures of the units next to said conducting sheets coöperating with said sheets to form four additional condenser 40 units, and said sheets being electrically connected with the sheath.

In witness whereof, I hereunto subscribe my name this 15th day of December, A. D., 1916.

MORTON SULTZER.
